(57) **CLAIM**

The ornamental design for a knife holder, as shown and described.

DESCRIPTION

FIG. 1 is a front view of a knife holder showing my new design;

FIG. 2 is a rear view of the knife holder;

FIG. 3 is a right side view of the knife holder;

FIG. 4 is a left side view of the knife holder;

FIG. 5 is a top view of the knife holder;

FIG. 6 is a bottom view of the knife holder;

FIG. 7 is a bottom front side perspective view of the knife holder in use; and,

FIG. 8 is a bottom front side perspective view of the knife holder.

The broken lines along the lateral edges of the knife holder are stitches forming no part of the claimed design. The other broken lines in FIG. 7 are illustrative of environmental structure forming no part of the claimed design.

1 Claim, 8 Drawing Sheets
